(57) **CLAIM**

The ornamental design for a display screen or portion thereof with animated graphical user interface, as shown and described.

DESCRIPTION

FIG. 1 is a front view of a display screen or portion thereof with animated graphical user interface showing a first image of the claimed design; and, FIG. 2 is a second image thereof.

The outermost broken lines in FIGS. 1-2 show a display screen or portion thereof, and form no part of the claimed design. The other broken lines in FIGS. 1-2 show portions of the animated graphical user interface that form no part of the claimed design.

The appearance of the animated images transitions between the images shown in FIGS. 1-2. The process or period in which one image transitions to another forms no part of the claimed design.
